US00D958876S

(12) United States Design Patent (10) Patent No.: US D958,876 S
Sun (45) Date of Patent: * Jul. 26, 2022

(54) PAPER SHREDDER

(71) Applicant: DONGGUAN SUNTECH ELECTRONICS CO., LTD.,
 Dongguan (CN)

(72) Inventor: Yicheng Sun, Dongguan (CN)

(73) Assignee: DONGGUAN SUNTECH ELECTRONICS CO., LTD.,
 Dongguan (CN)

() Term: 15 Years

(21) Appl. No.: 29/789,383

(22) Filed: Sep. 20, 2021

(51) LOC (13) Cl. 18-04

(52) U.S. Cl.

USPC D18/34.5

(57) CLAIM

The ornamental design for a paper shredder, as shown and described.

DESCRIPTION

FIG. 1 is a perspective view of a paper shredder, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the paper shredder that form no part of the claimed design.

1 Claim, 7 Drawing Sheets
